PAPER MAKING MACHINE

Original Filed July 20, 1926

UNITED STATES PATENT OFFICE

WILLIAM H. MILLSPAUGH, OF SANDUSKY, OHIO, ASSIGNOR TO THE PAPER & TEXTILE MACHINERY COMPANY, OF SANDUSKY, OHIO, A CORPORATION OF OHIO

PAPER-MAKING MACHINE

Original application filed July 20, 1926, Serial No. 123,757. Divided and this application filed January 21, 1929. Serial No. 333,836.

This invention relates to paper-making machines, and aims to provide an improved machine for use in the manufacture of laminated or plural-ply paper. The subject-matter of the invention is disclosed in my application filed July 20, 1926, Serial No. 123,757, of which this application is a division.

An illustrative machine embodying the invention is shown in the accompanying drawing, which represents a longitudinal sectional view of the machine.

The operation of the machine involves the simultaneous production of a plurality of wet paper sheets by vacuum-induced formation over suction rolls, and bringing the sheets together and bonding them into a unitary plural-ply sheet. The particular machine selected for illustration is adapted for the manufacture of paper up to six plies. The machine has in this instance six vacuum-forming cylinders 1^a, 1^b, 1^c, 1^d, 1^e and 1^f, provided by suction rolls of appropriate character for maintenance of desired vacuum areas. These cylinders consist of closely perforated metal shells, suitably mounted and driven. Their directions of rotation are indicated by arrows in the drawings. Endless strainer mediums preferably of fine wire cloth, hereinafter called the wires, are entrained around and driven by the cylinders. These wires are respectively designated by the symbols 2^a, 2^b, 2^c, 2^d, 2^e and 2^f. The directions of travel of the wires are indicated by arrows in the drawings.

The suction rolls and associated equipment may be of the character described in my aforesaid application, and will be briefly described as follows.

Associated with each roll is a vat 3 to hold liquid stock for paper production on or against a segment of the cylindrical forming surface provided by the wire covered portion of the roll. It will be understood that the liquid is continuously supplied to and maintained at a desired level in the vat by appropriate means. In each cylinder is a stationary suction box 4 having its open side bearing against the interior surface of the cylinder, providing a vacuum chamber 5 confronting the liquid body and extending to a

point above the liquid level. There is also provided in this instance, as a separate compartment of the suction box, a supplemental vacuum chamber 6 in each cylinder. The suction chamber 5 of each roll communicates through a pipe connection at 5^a with apparatus which will maintain in said chamber a suitable vacuum for inducing the wet sheet formation while at the same time drawing off the water removed in the process of forming the wet sheet of paper. The supplemental suction chamber 6 of each roll is similarly connected with a suitable vacuum pump through a pipe connection at 6^a.

Considering the operation of any individual suction roll or vacuum-forming cylinder, for instance the cylinder 1^a, the direction of rotation is such that the wire is carried upwardly past the contacting body of liquid stock. As the cylinder and wire move past the vacuum chamber 5, the suction forcibly withdraws water from the liquid body through the area of the wire in contact therewith, causing the continuous deposition on the wire of a web of paper pulp and the removal therefrom of a large amount of water. The continued action of the forming vacuum on the sheet as it emerges from and after it leaves the liquid, causes the deposited fibers to be firmly held and compacted against the corrosive action of any surplus moisture or pulp which may drain back into the vat. This same holding action of the vacuum prevents thinning or washing away of the deposited web while it is passing through the liquid in the vat. Another effect of the vacuum is the passage of air through the web after it leaves the liquid and is exposed to the air. The air thus forced through the web carries with it more water in the form of spray or vapor. These several effects combine to produce rapidly a continuous, uniform, closely compacted sheet, obtaining an excellent formation. Further drainage and compacting of the paper sheet takes place as the sheet is carried over the supplemental vacuum chamber 6.

It will be understood that the speed of rotation of the cylinder, the degree of vacuum maintained in the suction box, and the con-

sistency of stock delivered to the vat, may be controlled according to the thickness and character of sheet to be made; that the construction of the vat and suction box equipment of the suction roll may be such as to permit adjusting the width of the forming area in accordance with the width of the sheet to be made; and that the liquid stock held on the cylinders may be maintained quiet or 5 agitated according to whether it is desired to produce paper of greater tensile strength lengthwise than transversely, or whether it is desired to produce papers of increased transverse strength; all as explained in my afore- 10 said application. For agitating the liquid stock in the vats so as to promote criss-cross disposition of the fibers, in the case of producing papers of increased transverse strength, or of substantially equal strength 15 both longitudinally and transversely, the vats are shown provided with agitators each comprising a reciprocating rod 7 carrying a series of spaced blades 7^a having concave edges in close proximity to the cylinder. By 20 reciprocation of the rods 7 the blades 7^a will move the liquid stock rapidly in opposite directions across the cylindrical forming surface.

As the wet sheets formed over the several 25 suction rolls are to be brought together and bonded into a unitary plural-ply sheet, it is desirable that the vacuum maintained in each of the supplemental vacuum chambers 6 be regulated or adjusted to "temper" the respective sheets or plies to the proper degree of 30 moisture content for good bonding. In the production of plural-ply paper, involving the uniting of separate formations of paper, the sheets to be united should carry a certain 35 amount of water for bonding purposes. If the sheets are left very wet, or too wet, as is apt to be the case in the production of plural-ply paper by ordinary commercial methods, then difficulties will be encountered through 40 crushing of the wet sheets if sufficient pressure be applied to make the perfect bond or union required. On the other hand, if too much water is withdrawn from the sheet, then the bonding is likely to be imperfect, and 45 the layers or plies will be liable to separate. It is therefore important to regulate the moisture content of the sheet in accordance with bonding requirements. With the illustrated 50 machine, the supplemental vacuum chambers 55 6 provide convenient means whereby the sheets, while on their carrying mediums, may be subjected to independently controlled vacuum action so as to force substantially uniformly through the respective sheets such 60 quantities of air as to carry off or expel sufficient moisture to bring the sheets to desired condition. In general, a minimum moisture content for perfect bonding is desirable, as 65 the quality of the paper is better if the bonding union be perfected at such minimum

moisture content. According to requirements, the vacuum maintained in the chambers 6 may be more or less than the vacuum for forming the sheet. In this connection it may be observed that the tempering of the sheets over the auxiliary vacuum chambers 6 may be practiced without limitation of speed or interference with the desired speed of rotation of the forming cylinders.

The machine is organized and arranged so that the sheets formed over the various suction rolls are deposited one upon another on a press felt 8. The direction of travel of the felt is indicated by the arrow. It will be observed that the suction rolls or vacuum-forming cylinders with their associated wires are arranged in pairs, each pair constituting a duplexing organization or means for making a two-ply sheet. The cylinders of each pair rotate in opposite directions as indicated by the arrows, and the wires associated therewith travel convergingly as shown to bring the sheets formed thereon into contact. Considering the pair of cylinders 1^a, 1^b and their wires 2^a, 2^b, it will be observed 70 that the coacting runs of the wires are trained in engagement with a suction transfer roll 9, the suction box of which is indicated at 9^a, whereby the sheet on wire 2^b is transferred by suction to the sheet on wire 2^a. Wire 2^b 75 passes around a guide roll 10, while the wire 2^a carrying the duplex or two-ply sheet passes around guide rolls 11 and 12 which deflect it against the felt over a suction transfer roll 13, the suction box of which is indicated at 100 13^a, whereby the duplex sheet on wire 2^a (or the single-ply sheet thereon in case only one of said cylinders 1^a, 1^b is used for formation) is transferred by suction to the felt. Similar equipment may be provided for the other 105 pairs of vacuum-forming cylinders and wires. Thus the suction transfer roll for transferring the sheet from wire 2^a to wire 2^b is indicated at 14, and the suction transfer roll 110 for transferring the sheet or combined sheets from wire 2^a to the felt 8 or sheet or sheets thereon is indicated at 15. The bottom guide roll for wire 2^a is indicated at 16, and the guide rolls for the wire 2^a at opposite sides of the suction transfer roll 15 are indicated 115 at 17 and 18. Likewise, referring to the pair of wires 2^a, 2^b running from the cylinders 1^a, 1^b, the suction transfer roll 19 effects transfer of the sheet from wire 2^b to wire 2^a, and the suction transfer roll 20 under the felt 120 causes the sheet or combined sheets on wire 2^a to deposit on the felt or sheets thereon. The bottom guide roll for wire 2^b is indicated at 21, and the guide rolls for holding wire 2^b over the suction transfer roll 20 are 125 indicated at 22 and 23. By the construction described, the several wet paper plies or sheets formed over the several suction rolls are successively deposited on the felt.

It will be understood that wet sheets may 130

be formed on any desired number of the vacuum-forming cylinders, and on either one or both cylinders of each pair. Considering the illustrative machine without the cylinders 1^a, 5 1^b, 1^c and their associated wires, the rest of the machine including the cylinders 1^a, 1^c, 1^b, associated wires 2^a, 2^c, 2^b and felt and associated suction transfer rolls 10, 15 and 21 makes a complete organization by which 10 plural-ply paper may be made by forming plies and bringing them into contact on the felt.

The combined sheets on the felt 8 are carried thereby through a press represented in this instance by a top press roll 24 coacting 15 with a bottom suction press roll 25, the suction box of which is indicated at 25^a. Guide rolls for the felt are indicated at 26 and tensioning rolls at 27. There is also shown a top felt 28 traveling around guide roll 29 20 and coacting with the felt 8 to carry the plural-ply sheet through the press.

It will be understood that the invention is not restricted to the particular embodiment shown and described.

25 What I claim as my invention, and desire to secure by Letters Patent, is:

1. A paper-making machine comprising a plurality of pairs of suction rolls and endless wires traveling therearound, each pair of said 30 wires arranged for bringing their respective sheets together on one of the wires of such pair, and an endless carrier and means associated with said carrier and with each of the wires carrying the pairs of sheets by which 35 the said pairs of sheets are transferred one upon another on said carrier.

2. A paper-making machine comprising a plurality of pairs of sheet-forming suction rolls and wires traveling therearound, said 40 wires arranged for bringing their respective sheets together; suction means associated with each pair of wires for transferring the sheet on one wire to that on the other; a felt in association with the wires to which the 45 sheets are transferred; and suction means in association with each of said last mentioned wires for transferring the sheet or combined sheets carried thereby to the felt.

3. A paper-making machine comprising a 50 plurality of pairs of oppositely revolving sheet-forming suction rolls and wires traveling around them, the respective pairs of wires having converging sheet-carrying runs; suction transfer rolls entrained by the respective 55 pairs of wires, whereby the sheet products of each pair of suction rolls are brought together as a duplex sheet and carried on one of the wires for such pair; a felt in association with the wires carrying the duplex sheets; and suction transfer rolls entrained by the felt and 60 said last mentioned wires, whereby the duplex sheets are successively deposited on the felt.

4. A paper-making machine comprising 65 suction rolls and wires running around them on which web sheets are formed over the rolls

by vacuum-induced formation, and a felt and a plurality of means associated with the felt and respectively associated with a plurality of wires by which the sheets are deposited on the felt.

5. A paper-making machine having, in combination, a plurality of means including suction rolls for forming a plurality of wet sheets by vacuum-induced formation, and means including a press felt and a plurality of transfer means in association with said felt and respectively associated with the respective sheet-forming means by which the wet sheets are brought together on the felt to form a plural-ply sheet.

6. A paper-making machine embodying a plurality of sheet-forming suction rolls and wires running around them on which wet sheets are formed over the vacuum areas of the rolls, and a felt cooperating with said wires in succession and to which the sheets carried by the wires are successively transferred.

7. A paper-making machine having a plurality of suction rolls and wires running around them on which wet sheets are formed over the vacuum areas of the rolls, a felt running in engagement with the respective wires, and suction transfer devices associated with the felt and the respective wires for transferring the sheets by suction from said wires to the felt.

8. A paper-making machine having a plurality of suction rolls and wires running around them on which wet sheets are formed over the vacuum areas of the rolls, a felt running in engagement with the respective wires, suction transfer rolls associated with the respective wires, and guide rolls whereby the wires are respectively held in engagement 105 with the felt and the latter held in engagement with the suction transfer rolls.

9. A paper-making machine having a plurality of suction rolls and wires running around them on which wet sheets are formed over the vacuum areas of the rolls, a felt running in engagement with the respective wires, and guide rolls whereby the respective wires are held in engagement with the felt.

10. A paper-making machine combining a plurality of pairs of oppositely revolving suction rolls and wires traveling around them on which wet sheets are formed over the vacuum areas of said rolls, said pairs of wires each arranged to bring the pair of sheets 110 formed thereon into contact and to carry off the contacting sheets by one of said wires, and a felt running in engagement with the wires carrying the said pairs of sheets and onto which the said pairs of sheets are successively 120 deposited.

In testimony whereof, I have signed my name to this specification.
